UNITED STATES PATENT OFFICE.

NICHOLAS ELLIS PORTER, OF LONDON, ENGLAND.

DERRICK FOR LOADING OR UNLOADING VESSELS.

SPECIFICATION forming part of Letters Patent No. 714,328, dated November 25, 1902.

Application filed July 21, 1902. Serial No. 116,374. (No model.)

To all whom it may concern:

Be it known that I, NICHOLAS ELLIS PORTER, marine surveyor, a subject of the King of Great Britain, residing at 101 Leadenhall 5 street, in the city of London, England, have invented a certain new and useful Improvement in Derricks for Loading or Unloading Vessels, of which the following is a specification.

10 In derricks as now usually constructed the derrick-boom is at its foot end jointed to a vertical pivot-pin, which can be dropped into a socket secured to the side of the mast or to a table or support extending around the mast. 15 Usually three such sockets are provided, one on either side of the mast and the third in the same longitudinal line as the mast. It is undesirable that the derrick-booms should be heavier than is necessary for being used 20 when raising a load of usual weight; but occasionally much heavier weights have to be lifted in or out, and to provide for this a special derrick-boom of two, three, or more times the strength of other booms has had to be 25 provided, and a specially strong socket has had to be secured to the deck for receiving its pivot-pin. These special heavy spare derrick-booms are costly, and owing to their weight are difficult to handle, and when out 30 of use and stowed away on the deck are always in the way, and being only wanted on rare occasions entail loss of carrying power to the ship. To avoid the necessity of providing such a special spare heavy derrick- 35 boom for being used when lifting an exceptionally heavy weight, I provide clamps, by which three of the derrick-booms used when lifting loads of usual weight can be clamped together, so as to form one boom of triangu- 40 lar cross-section, and I provide a special "gooseneck" or pivot-pin, the head of which is so formed that the ends of two of the booms can be jointed to it. I also provide a specially strong socket for this pivot-pin to be dropped 45 into. This socket may be secured to the deck, but preferably I secure it to the raised table, which carries the other sockets used when working with single derrick-booms, additional supports being provided to give the requisite 50 strength to the table. Usually I provide three clamps for clamping together the three booms, two for clamping them together at the ends

and the third for clamping them together at the center. Where the three booms are embraced by each end clamp, I place centrally 55 between them a hard wooden block with three faces, each suitably shaped to form a bed for a portion of the circumference of each boom to be held against. Each clamp may be in two parts and the end portions of the two 60 parts made to lie parallel with one another, so that they may be drawn together by screw-bolts. For the upper end clamp two of the ends so bolted together are suitably formed for the upper block of the lifting-tackle or 65 purchase-fall to be carried by them, and the other two ends, which are bolted together, suitably formed for the supporting-tackle to be connected to them. Similarly the other clamps may be made to carry rollers for the 70 lifting rope or chain of the purchase-fall to be led over. Other clamps are also provided to be clamped onto the derrick-booms when the booms are to be used singly and are similarly formed for the lifting and supporting 75 tackle and for guide-rollers to be carried by them. In place of clamping three derrick-booms together, as above described, two or other number of booms might similarly be 80 clamped together.

The improvements are shown in the drawings annexed.

Figure 1 is a side elevation of a derrick having a built-up boom composed of three lighter booms clamped together, as above described. 85 Fig. 2 is a side elevation, on a larger scale, of the lower end of the built-up boom, with two of the lighter booms of which it is composed jointed to the head of a vertical pivot-pin. Fig. 3 is a section of the same on the line a 90 b, Fig. 2. Fig. 4 is an end elevation of a clamp by which the upper ends of the three light booms are clamped together, the booms being shown in section. Fig. 5 is a side elevation of the same. Fig. 6 is an end elevation of a clamp for clamping together the booms near the center of their length, the booms being shown in section. Fig. 7 is a similar view of a clamp for clamping together the lower ends of the light booms. Fig. 8 is 95 a side elevation of one of the light booms jointed to a vertical pivot-pin when it is to be used singly. Fig. 9 is an end elevation of a clamp by which the upper end of the light

boom is then embraced and which is adapted to carry a pulley-block for the lifting-tackle. Fig. 10 is an end elevation of a clamp by which the light boom may be embraced at 5 any desired part of its length and adapted to carry a roller for the lifting-chain to pass over.

In Figs. 1, 2, and 3 the socket for receiving the vertical pivot-pin of the heavy built-up 10 boom is shown to be carried by a raised table secured to a mast and supported by strong supports from the shelter-deck and upper deck of a vessel; but the socket might be mounted in any other suitable position.

15 In Fig. 1, A is the shelter-deck; B, the upper deck; C, a table secured to the mast D. E represents supports for this table, extending upward from the upper and shelter decks.

F is a vertical pivot-pin dropped into a 20 socket formed to receive it in the table C. F' represents brackets extending upward from the head of this pivot-pin.

G represents three light booms clamped together, as above described, to form a built-up 25 boom triangular in cross-section. Each light boom has an eye G' secured to its lower end, as usual. The eyes at the lower end of two of these light booms pass into spaces between the brackets F'.

30 H is a horizontal pin passed through the brackets and through the two eyes which lie between them.

I I' I² are clamps holding together the three 35 light booms G. The upper clamp I (shown separately at Figs. 4 and 5) carries a pulley J, serving as the upper pulley of the lifting-tackle and a pulley K for the supporting-tackle. Parts only of these pulleys are shown in Figs. 4 and 5.

40 The lifting-tackle and the supporting-tackle may be arranged in any desired way. The arrangement shown is a convenient one. The other clamps I' I² may, as shown, each carry a roller for the lifting chain or rope to pass 45 over. The light booms G being usually of

larger diameter at the center than at the ends, filling-blocks L are provided for placing between at the parts where they are embraced by the end clamps, as shown in Figs. 4, 5, and 6.

If in place of the built-up boom being formed of three light booms clamped together it were formed of two or four or other number of light booms, then the form of the clamps would be modified accordingly.

When any one or other of the light booms G is to be used singly, then a clamp, such as shown at Fig. 9, is clamped to its upper end to carry pulleys for the lifting and supporting tackles. Other clamps, such as shown at Fig. 10, may also be made to embrace any desired parts of the boom to carry rollers for the lifting chain or rope to pass over.

What I claim is—

1. The combination of a vertical pivot-pin, 65 a built-up boom composed of lighter booms clamped together and a horizontal joint connecting the lower end of the built-up boom to the head of the vertical pivot-pin.

2. The combination of a vertical pivot-pin, 70 a built-up boom of triangular cross-section composed of three light booms clamped together and a horizontal joint connecting the lower ends of two of the light booms to the head of the vertical pivot-pin.

3. The vertical pivot-pin with enlarged head having brackets extending from it and spaces between the brackets to admit of eyes on more than one light boom being jointed to them with the joints in line with one another. 80

4. A built-up derrick-boom composed of lighter booms clamped together, each such lighter boom having a metallic eye fixed to its lower end so that each may be used separately when unclamped from the others.

NICHOLAS ELLIS PORTER.
